UNITED STATES PATENT OFFICE.

RALPH D. SMALL, OF CHICAGO, ILLINOIS.

SHOE-TREE.

Application filed December 6, 1924. Serial No. 754,247.

To all whom it may concern:

Be it known that I, RALPH D. SMALL, a citizen of the United States, residing at Chicago, in the county of Cook and the State of Illinois, have invented a certain new and useful Improvement in Shoe-Trees, of which the following is a full, clear, concise, and exact description.

My invention relates to shoe trees and has a number of objects and advantages in view.

In accordance with one characteristic of the invention the shoe tree has a shoe horn incorporated therewith to be available for use instantly when the shoe tree is removed.

In accordance with another characteristic of the invention the toe and heel pieces of the tree are relatively adjustable laterally of the tree that is thus adaptable to lasts of differing curvatures. The toe and heel pieces are desirably joined by a link that is in swinging assembly with both of these pieces and is curved upwards from the base of tree adjacent the toe piece to snugly underlie the same when the tree is to be adjusted for packaging.

In accordance with another characteristic of the invention, a friction clutch is employed which has two complementary members, one upon the heel piece and the other upon the toe piece. One of the clutch members extends from the tree piece carrying it toward the other tree piece, and the other clutch member has gripping frictional engagement at different places along the first whereby the length of the shoe may be adjusted by merely relatively slipping the clutch members along the tree, no spring bolts or other supplemental devices being required.

The toe piece of the tree is preferably longitudinally divided and where such a toe piece is employed I use a wedge that is interposed between the sections of the toe piece to spread them into tight engagement with the toe of the shoe within which the tree is inserted. I also provide means for maintaining the toe sections in suitable relation in all adjustments effected by the wedge.

The invention has other characteristics and will be more fully explained in connection with the accompanying drawings in which Fig. 1 is a side view showing the preferred form of tree inserted within a shoe; Fig. 2 is a plan view; Fig. 3 is a plan view of the heel piece straightened into align-

ment with its link that couples it with the toe piece, the shoe horn being shown as adjusted for use; Fig. 4 is a longitudinal sectional view showing the tree collapsed for packaging or storage; Fig. 5 is a bottom view of the front part of the tree; Fig. 6 is a sectional view on line 6—6 of Fig. 4; Fig. 7 is a sectional view on line 7—7 of Fig. 4; Fig. 8 is a rear view of the toe portion of the tree; and Fig. 9 is a sectional view on line 9—9 of Fig. 4.

The heel piece is T-shaped, being inclusive of an arcuate horizontal portion 1 conforming to the curvature of the heel, and a forwardly projecting stem 2. The toe piece is preferably longitudinally divided into sections 3 and 4. A device is employed for connecting the heel and toe pieces which is preferably inclusive of a tongue or link 5 flexibly connected at its front end in any suitable way with the toe piece, and an upright link 6 normally transverse to the tongue 5 and stem 2 and pivotally connected with the latter to have vertical swinging connection therewith. Said tongue or link 5 extends toward the heel piece and is normally above its stem 2. The link 6 is inclusive of a closed loop portion 6' through which the tongue or link 5, that is preferably a thin bar, is passed, the parts 5, 6' constituting the complementary members of a ring friction clutch whose member 6' has changeable gripping frictional engagement with and at different places along clutch member 5 to adjust the length of the tree. When the shoe tree is being adjusted for use, the clutch members are relatively positioned to suit the tree to the length of the shoe. The tree is inserted within the shoe in an initially upwardly buckled adjustment, whereafter the button 7 upon the rear end of the tongue or link 5 is pressed to straighten the tree into tight engagement with the heel and toe of the containing shoe.

The shoe horn 8 is pivotally connected at its tip with the stem 2 as indicated at 9 and may be swung crosswise of this stem into a position in which it may be used, when the tree is withdrawn from the shoe. The shoe horn is thus instantly available for use in connection with the shoe from which the tree has just been removed. When the shoe horn is adjusted to an out-of-service position, it is retained in such position by the engagement of its base end with the ridge formation 10 upon the top side of the heel

part 1, the horn being of a length requiring it to be slightly sprung into this engagement.

As illustrated, the connecting device 5, 6 has a horizontal and preferably a universal swinging connection with the toe piece, which permits the heel and toe pieces to be relatively adjustable laterally of the tree, whereby the tree may be adjusted to suit 10 lasts of differing curvatures.

Where a divided toe piece is employed, my invention also includes improved mechanism for adjusting the sections of the toe piece laterally of each other and for maintaining these toe sections in cooperative relation in their various relative adjustments. This mechanism includes a forwardly tapering horizontal wedge 11 with whose rear end the forward end of link 5 is universally 20 joined as indicated at 12. The converging or wedging faces of the wedge engage the inner sides of the abutment posts 13 which depend from the toe sections, the toe piece being in the form of an inverted metallic 25 dish to receive its adjusting mechanism and to afford ample ventilation. Other abutment posts 14, spaced apart from the posts 13 longitudinally of the tree, are embraced by a yoke 15 integrally formed with the 30 wedge and having inner sides sloping similarly to the converging sides of the wedge, to limit the spreading action of the wedge at the forward part of the toe piece and to assist in bringing the toe sections together. 35 Links 16 are pivotally connected at their outer ends with posts 13 and are pivotally connected with each other at their inner ends. The pin 17 by which the inner ends of the links 16 are connected has sliding connection with the wedge by being projected 40 through the narrow longitudinal slot 18 formed in the wedge. By this arrangement the toe sections are constrained to move equal distances from and toward their 45 dividing plane. The relative movements of the toe sections are perpendicular to this plane, a result which is further assured by the horizontal transverse pin 19 at the forward end of one toe section which is received within a socket 20 upon the other toe 50 section.

The shoe tree is collapsible into smaller space, and in order that this space may be reduced as much as possible, the forward 55 end of link 5 that is adjacent the toe piece, is upwardly curved so that it may more closely underlie the toe piece, as indicated in Fig. 4.

Changes may be made without departing 60 from my invention.

Having thus described my invention, I claim:—

1. A shoe tree including a toe piece divided longitudinally of the tree into sections; a wedge interposed between and engaging abutments provided upon said sections to spread said sections apart, and two links, one individual to and connected at its outer end with each toe section, said links having sliding connection at their inner ends with said wedge. 65

2. A shoe tree including a toe piece divided longitudinally of the tree into sections; a wedge interposed between and engaging abutments provided upon said sections; and a member upon said wedge embracing additional abutments provided upon said toe sections and that are spaced apart from the aforesaid abutments longitudinally of the tree, the lines of engagement of the additional abutments and the embracing member being directed similarly to the wedging sides of the wedge. 75

3. A shoe tree including a toe piece divided longitudinally of the tree into sections; a wedge interposed between and engaging abutments provided upon said sections to spread said sections apart, two links, one individual to and connected at its outer end with each toe section, said links being assembled at their inner ends; and a member upon said wedge embracing additional abutments provided upon said toe sections and that are spaced apart from the aforesaid abutments longitudinally of the tree, the lines of engagement of the additional abutments and the embracing member being directed similarly to the wedging sides of the wedge to limit the spreading action of the wedge. 85

4. A shoe tree including a toe piece divided longitudinally of the tree into sections; a wedge interposed between and engaging abutments provided upon said sections to spread said sections apart; two links, one individual to and connected at its outer end with each toe section, said links having sliding connection at their inner ends with said wedge; and a member upon said wedge embracing additional abutments provided upon said toe sections and that are spaced apart from the aforesaid abutments longitudinally of the tree, the lines of engagement of the additional abutments and the embracing member being directed similarly to the wedging sides of the wedge to limit the spreading action of the wedge. 100

In witness whereof, I hereunto subscribe my name.

RALPH D. SMALL.
